Primary Examiner — Cynthia Underwood(74) *Attorney, Agent, or Firm* — Mark P. Stone**CLAIM**

The ornamental design for "eye bolt", as shown and described.

DESCRIPTION

FIG. 1 is a front perspective view of a first embodiment of an "eye bolt", showing the new design;

FIG. 2 is a front elevational view thereof, the rear elevational view being identical to the front elevational view;

FIG. 3 is a perspective view thereof taken from the top;

FIG. 4 is a right side elevational view thereof;

FIG. 5 is a left side elevational view thereof;

FIG. 6 is a top plan view thereof;

FIG. 7 is a bottom plan view thereof;

FIG. 8 is a front perspective view of a second embodiment of the "eye bolt", showing the new design;

FIG. 9 is a front elevational view thereof, the rear elevational view being identical to the front elevational view;

FIG. 10 is a perspective view thereof taken from the top;

FIG. 11 is a right side elevational view thereof;

FIG. 12 is a left side elevational view thereof;

FIG. 13 is a top plan view thereof; and,

FIG. 14 is a bottom plan view thereof.

The broken lines in the drawings depict environmental subject matter/or parts of the eye bolt only and form no part of the claimed design.
